UNITED STATES PATENT OFFICE.

BERNARD A. SCHRODER, OF BIRMINGHAM, ALABAMA, ASSIGNOR TO AUTOMATIC GAS RADIATOR COMPANY, A CORPORATION OF ALABAMA.

HEATING SYSTEM.

1,280,871.

Specification of Letters Patent.

Patented Oct. 8, 1918.

Application filed February 12, 1915. Serial No. 7,801.

To all whom it may concern:

Be it known that I, BERNARD A. SCHRODER, a citizen of the United States of America, residing at Birmingham, in the county 5 of Jefferson and State of Alabama, have invented certain new and useful Improvements in Heating Systems, of which the following is a specification.

My invention relates to heating systems 10 in which a number of radiators are employed and each provided with individual valve controlled burners for gaseous fuel and in which the products of combustion are positively drawn off by an exhaust fan or blower 15 from the several radiators through a manifold piping system and discharged into the atmosphere.

In heating systems of this character where 20 gas is burned in the radiators, it is of vital importance that there should be a common control of the gas supply to the several radiators which will automatically respond if the exhaust draft stops for any reason, and instantly shut off the gas supply from 25 all radiators in the entire heating system so that any possibility of escape of gas into rooms or compartments is avoided. In systems of this character it has heretofore been attempted to control the gas valves for the 30 several radiators automatically by the suction pressure as it existed at the several radiators, or by controlling the valves by an electric circuit supplied by a generator driven with the fan. The objection to the 35 former arrangement is that the suction action of the exhaust fan varies at each radiator in proportion to the distance of such radiator from the fan and inasmuch as the suction would have to be strong enough 40 throughout the system to make sure of the control of the most remote radiator gas valves, it follows that an excessive suction will result at the radiators nearest the suction fan. Moreover, such systems necessarily 45 require so strong an exhaust or suction that the consumption of the gas is high and the cost of operation expensive.

According to my invention I propose to utilize as low an exhaust pressure as will 50 create a light draft sufficient to insure the withdrawal of the products of combustion and gases from the radiators throughout the system and all of the gas valves for the several radiators are controlled by a common 55 operating means which is made automatic-

cally responsive to the suction or draft at or near the fan. In other words, I provide a master control which is responsive to the draft or suction action where it is most vigorous and effective in the manifold system 60 and utilize a relay power, such as electricity, air or steam pressure, or like power transmission mediums to reach out and effect the closing of the distant individual radiator gas valves throughout the whole 65 system.

A further important feature of my invention consists in means for controlling the suction action at the different radiators so that the draft created thereby throughout 70 the whole radiation system and regardless of distance from the suction fan, will be substantially uniform. By interposing a valve or damper in the outlet from each radiator, I am enabled to regulate the volumetric flow 75 of the air, gas and products of combustion from each radiator which enables me to maintain so light a draft throughout the piping exhaust system that the economic consumption of gas is not adversely effected 80 thereby and there will be a minimum consumption of power in maintaining the draft.

My invention further comprises the novel details of construction and arrangements of parts, which in their preferred embodiment 85 is hereinafter more particularly described, reference being made to the accompanying drawings which form a part of this specification, and in which:—

Figure 1 is a view showing a heating sys- 90 tem having the electric central control for the radiator gas valves.

Fig. 2 is an enlarged end view of a radiator section broken away to show the gas valve control mechanism and the draft 95 damper.

Fig. 3 is a view of the modification of the blower operated mechanism for controlling the radiator gas valve.

Similar reference numerals refer to similar parts throughout the drawings.

The radiators 1 may be of any standard design and are preferably provided in their bottoms with a longitudinal burner 2 which is connected by an elbow 3 to a valve casing 5 to which gas is delivered by a branch pipe 4 of the gas supply piping system. In each casing is arranged a valve 6 and a seat 7 therefor, the valve being adapted to seat by gravity and having an enlarged head 8 110

which is adapted to be attracted by a magnet 9 disposed within the casing 5 and having its wires 10 and 11 leading outwardly therefrom through suitably insulated openings. A cap 5 plate 12 closes the top of casing 5 and carries the magnet. The bottom of the radiator sections are provided with openings 13 for supplying air to the burner. The wires 10 and 11 form a local control circuit for 10 each radiator or each group of radiators and a thermostatic make and break control switch 14 may be interposed in each branch circuit. The several branch control circuits are connected up to the main control leads 15 15 and 16 which lead to the contact points 17 and 18 of the master control switch. This master control switch comprises a sensitive diaphragm 19 which is connected by a small rod 20 to a switch 27 which is adapted to 20 open or close the master circuit at the contacts 17 or 18, according to the position of the diaphragm. The diaphragm 19 may be of any suitable construction and is attached suction pressure tight over a bottom opening 25 in a hollow casing 21 having a threaded nipple 28 adapted to screw into a fitting 29 in the manifold suction exhaust pipe 22 at a point adjacent to the suction fan 23 which is driven by a motor 30. This suction pipe 30 22 is connected by branch pipes 24 with the upper ends of the several radiators 1 and serves to draw off the products of combustion and the gases therefrom and to prevent the escape of obnoxious gases into the compartment heated. The fan creates a light 35 draft through the radiators which insures the proper combustion of the gases therein and delivers the exhaust products of combustion to a stack pipe 25 through which they are discharged into the outer atmosphere. I provide a suitable valve or damper 26 in each branch pipe 24 preferably at the radiator so that the draft therethrough can be regulated.

45 I have stated that the master suction control switch is located at a point in the suction exhaust line adjacent to the fan. The object of this is to place the diaphragm where the suction action is strong enough to 50 make certain and reliable the operation of the master control switch, and hence it may be placed at any convenient point where these conditions prevail. The diaphragm is so designed and connected to the switch that, 55 upon the abnormal lowering or drop of the suction pull in the pipe 22, it will open the master control circuit and thereby release all of the radiator gas valves by deenergizing their magnets so that all that are open 60 at the time will close automatically and shut off the radiators, which cannot be again started up until the suction has been restored to normal conditions in the exhaust pipe 22. I do not undertake to state just 65 how close it is desirable to locate the dia-

phragm to the suction fan as this depends upon the suction conditions in the pipe 22 and the power of the fan. Inasmuch as for the sake of economy in gas consumption, I propose to use as light a suction as will insure the proper removal of the products of combustion from the most remote radiators in service, it will be advisable to place the diaphragm close enough to the fan to enable the suction action of the fan to hold the control circuit normally closed against sufficient resistance on the part of the diaphragm to make certain and reliable its opening movement and the opening of the master control circuit when the suction is abnormally diminished or interrupted. By adjusting the several valves or dampers 26, I obtain a substantially uniform draft throughout the radiators of the heating system, the valves for the radiators nearest the suction fan being but partly open and those for the radiators farther away being opened more widely until at the most remote radiators the dampers can be full open. This prevents the nearer radiators bleeding the suction to the disadvantage of the more distant radiators. Moreover by cutting off radiators from the suction system the power consumption at the fan can be reduced to a minimum for the requirements of the heating system. I provide the lower end of the suction pipe 22 with a trap drain 31. Obviously the magnets may be designed for direct or alternating current and the diaphragm may be adapted to either open or 90 close the master circuit when the suction is interrupted, the other parts being designed accordingly so that the interruption of the suction will effect the closing of the individual radiator valves.

105 It will be understood that I do not desire to limit myself to a diaphragm as the suction control means for the master control circuit, as any other equivalent mechanism may be employed with equal advantage 110 without departure from the principle underlying my invention. For example, in Fig. 3 I show a very simple and effective means for utilizing the direct action of the draft to control the master circuit. Here the stack pipe 25 is provided near the blower outlet with an offset chamber 32, in the lower part of which I pivot a vane or blade 33 having a shank 34 which projects through a small opening in the chamber 32 and has a contact plate 35 suitably insulated therefrom and adapted to contact with circuit terminals 17^a and 18^a when the vane is swung upwardly by the draft. The vane is slightly unbalanced so that it will swing down over 115 the blower outlet when the draft becomes abnormally low or is interrupted, thereby breaking the master circuit. A light draft sufficient to carry off the products of combustion from the radiators will be sufficient to 120 125 130

swing the vane upwardly to the dotted line position and hold it there, in which position the master circuit is closed by the plate 35.

Having thus described my invention, what I claim as new and desire to secure by Letters Patent, is:—

1. In a gas burning heating system, a plurality of heaters having individual fuel supply valves, means to carry off to the atmosphere the products of combustion from said heaters, a master control means adapted to simultaneously and positively close said fuel supply valves, and means responsive to pressure conditions of the draft at a predetermined point in the heating system to operate said master control means.

2. In a gas heating construction, the combination with a master electric circuit, and a plurality of heaters having individual fuel supply valves, of electric local circuits connected with the master circuit and controlling said valves, thermostatic circuit closers arranged in each local circuit, means for delivering the products of combustion from the heaters to the atmosphere, and a circuit closer located remote from the heaters and active under pressure variations in the last named means to control the master circuit.

3. In a heating system, in combination, a plurality of gas burning heaters having individual fuel supply valves, electric means to control from a distant point the closing of said several supply valves, a draft stack, a piping system for carrying off the products of combustion from said heaters to said stack, a blower to induce a positive draft through said piping system, and mechanism disposed between the stack and said several

heaters and which is responsive to the decrease or interruption of draft to place said distant control means in operation to shut off the gas from all the heaters.

4. In a gas burning house heating system, a plurality of independent gas burning heaters distributed about the house, a common exhaust piping system adapted to carry off their products of combustion, a blower to induce a draft through said piping system, and a common electrically operated control mechanism located adjacent to the blower and directly controlled by the air pressure in said piping system near the blower for simultaneously shutting off the fuel from all of said heaters, substantially as described.

5. In a heating system, a plurality of gas burning radiators having each an outlet flue and a valve means to shut off its fuel supply, a draft stack with which said flues connect and through which the products of combustion from the radiators are discharged into the outer atmosphere, electric means adapted to effect the closing of each valve means, a master circuit which includes said several electric means, and a control means located at a remote point from the radiators for said master circuit which is responsive to variations in the stack draft and is adapted to effect the interruption of fuel supply to the radiators when the draft decreases abnormally.

In testimony whereof I affix my signature in presence of two witnesses.

BERNARD A. SCHRODER.
